UNITED STATES PATENT OFFICE.

ISAAC M. WARNER, OF UNION CITY, MICHIGAN, ASSIGNOR TO FRANK C. BOISE, OF UNION CITY, MICHIGAN.

WIRE-FENCE STRETCHER.

SPECIFICATION forming part of Letters Patent No. 736,323, dated August 11, 1903.

Application filed March 28, 1902. Serial No. 100,465. (No model.)

To all whom it may concern:

Be it known that I, ISAAC M. WARNER, a citizen of the United States, residing at Union City, in the county of Branch and State of Michigan, have invented a new and useful 5 Wire-Fence Stretcher, of which the following is a specification.

My invention is an improved wire-fence stretcher; and it consists in the peculiar construction and combination of devices herein-after fully set forth and claimed.

The object of my present invention is to effect improvements in the construction of the stretcher-bar.

15 In the accompanying drawings, Figure 1 is a side elevation of a wire-fence stretcher embodying my improvements, showing the same in operative position. Fig. 2 is a detail sectional view showing a portion of the stretcher-bar and the stretcher-wheel mounted therein. Fig. 3 is a front elevation of the same. Figs. 20 4 and 5 are detail elevations showing a modification.

25 My improved stretcher-bar comprises the two sections 1, which are flattened bars of iron, steel, or other suitable material, provided at suitable points, here shown as near their upper and lower ends, with lateral outstanding offsets 2, which form openings 3 sufficient in size to receive the stretcher-wheel 4 and to clear the stretcher-chains 5. The said sections 1 are secured together by bolts 6, and it will be understood that in operation the sections of the stretcher-bar are 30 clamped on opposite sides of the runner-wires α of the fence or of a fence fabric. The vertical portions 2 α of the lateral outstanding offsets of the stretcher-bar sections are provided with inclined slots 7, which form the 35 bearings for the shaft or axle 8, which carries the stretcher-wheel 4, so that the latter may be detachably mounted in said lateral outstanding offsets and successively employed at different portions of the stretcher-bar in 40 stretching the upper or lower running wires or the upper and lower portions of a wire-fence fabric. The stretcher-wheel is provided with radial sprockets 9, which are adapted to engage the openings in the links 45 of the stretcher-chains. In each of the openings 3, in one side thereof, is a pawl 10, which

is pivotally connected to one of the lateral outstanding offsets, as by a bolt 11. The stretcher-wheel has on one side thereof a ratchet-wheel 12, and the latter is engaged by 55 one of the pawls 10, as will be understood. One end of the shaft or axle 8 projects a sufficient distance beyond the stretcher-bar to form the pivot for the operating-lever 13. The same is provided with a pawl 14, which 60 is also adapted to engage the ratchet-wheel 12. It will be understood that when the lever 13 is oscillated the pawls 10 14 coact with the ratchet-wheel 12 to rotate the stretcher-wheel by a step-by-step movement, and hence the 65 stretcher-wheel being in engagement with one of the stretcher-chains stretches the fence to the requisite extent.

In the opposing sides of the stretcher-bar sections 1 at appropriate points, here shown 70 as above the offsets 2, are openings 15, which extend from the front side of the stretcher-bar to the rear side thereof, and in the said openings are disposed the shanks of eyebolts 16. Holder-hooks 17 of suitable construction, 75 adapted to grapple and hold the stretcher-chains under tension, are connected to the eyes of the bolts 16 by chains 18.

In Figs. 4 and 5 I show a modification, in which there is a clutch member 12 α on the 80 outer side of the ratchet-wheel 12, and the lever 13, which is fulcrumed on the shaft 8, has on its inner side a clutch member 13 α . The lever is movable laterally on the shaft 8, so that the clutch member 13 α may be engaged 85 with and disengaged from the clutch member 12 α at will. It will be understood that by appropriately operating the lever the ratchet-wheel, and hence the chain-wheel on the shaft, may be rotated by a step-by-step movement, the pawl 10 by engagement with the ratchet-wheel, as before described, preventing reverse rotation of the ratchet and chain wheels.

No claim is made therein to the hook connected to the stretcher-bar and adapted to engage the chain to lock the stretcher-bar thereto when the chain is under tension and relieve the drawing means of the stress exerted thereon by the chain, as the same is claimed in my co-pending application for Letters Patent of the United States, Serial No. 95,986. 95 100

Having thus described my invention, I claim—

A wire-fence stretcher-bar comprising a pair of sections and bolts clamping them together, said sections being formed at points intermediate their ends with integral lateral outstanding offsets, forming openings in the bar, the vertical portions of said offsets having inclined bearing-slots open at their upper ends on one side of the stretcher-bar, in combination with a shaft having a chain-wheel, a lever, and coacting devices whereby the chain-

wheel may be rotated by the lever, said shaft being adapted to be mounted in the said bearing-slots, whereby the lever and chain-wheel are shiftable on the stretcher-bar, substantially as described.

In testimony that I claim the foregoing as my own I have hereto affixed my signature in the presence of two witnesses.

ISAAC M. WARNER.
